UNITED STATES PATENT OFFICE

2,631,052

LATCHING AND RELEASING MECHANISM
FOR REFRIGERATOR DOORS

John Vincent Jamison, Jr., Hagerstown, Md., assignor to Jamison Cold Storage Door Co., Hagerstown, Md., a corporation of Maryland

Application October 12, 1949, Serial No. 120,947

1 Claim. (Cl. 292—254)

1

The invention relates to new and useful improvements in a latching and releasing mechanism for refrigerator doors and more particularly for use with refrigerator doors of the overlapping superfreezer type wherein the door is held closed by a spring actuated keeper mounted on the door frame and engaging a lug on the door when the door is in closed position. Doors of this overlapping type vary in thickness according to the temperature and humidity and vapor conditions of use, and often with heavy doors two or more latching devices are used to hold the door tightly sealed when closed, which is of vital importance in today's sub-zero refrigerated rooms.

An object of the invention is to provide a latching and releasing mechanism that is adapted for use on overlapping refrigerator doors of various thicknesses.

A further object of the invention is to provide a latching and releasing mechanism which may be used for simultaneously releasing two or more keepers.

A still further object of the invention is to provide a latching and releasing mechanism which, when the door is slammed to the closed position, will firmly compress the door against the gasket making an airtight seal and when pulled upon will release the keeper or keepers, break the gasket seal, and then serve as a means for opening the door.

In the drawings, which show by way of illustration one embodiment of the invention,

Figure 1 is a view in front elevation showing the improved latching and releasing mechanism applied to a refrigerator door having spring actuated keepers for holding the door in closed position;

Figure 2 is a sectional view on the line 2—2 of Figure 1; and

Figure 3 is a sectional view on the line 3—3 of Figure 1.

In the drawings there is illustrated an overlapping superfreezer door. The door as a whole is indicated at 1, and the door frame with which the door is associated is indicated at 2. There is a gasket 3, preferably attached to the door, which engages the door jam when the door is in closed position for sealing the opening leading to the refrigerator chamber. In the present embodiment of the invention there are shown three spring actuated latching devices indicated at 4, 4, 4 in the drawings for holding the door closed. Applicant's latching and releasing mechanism operates independently upon these latches and it may be used for one or for more latches, depending upon the desired latching equipment for

2

the type of door to which it is applied and the varying conditions under which the door is used.

Each latching device includes a housing 5 in which is mounted a keeper 6. The keeper 6 is provided with a head 7 which is tapered on its inner face which is indicated at 8 and is also tapered on its outer face as indicated at 21. A spring 9, located in the housing 5, bears at one end against the head and at its other end against the rear wall of the housing. The keeper is therefore spring pressed so that it projects outward from the housing, but is capable when pressed upon to move into the housing, thus compressing the spring. The stem of the keeper is provided with the stop 10 which engages the housing and limits the outward movement of the keeper. Mounted on the edged portion 11 of the overlapping door 1 is a bracket 12 carrying a lug 13 which cooperates with a keeper 6 in holding the door closed. When the door is moved to closed position the lug 13 contacts the tapered face 21 of the head 7 and forces the keeper into the housing until the lug has passed the end of the keeper and then the keeper moves outwardly and the tapered face 8 will wedgingly force the door and gasket 3 into tight sealing contact with the door frame.

As shown in Figure 1, there are three of these latching devices and the housings thereof are adjustably secured to the door frame by bolts 14, 14 passing through slots 15 in the base of the housing. These slots permit the housings to be adjusted toward and from the edge of the door.

In order to wedge the door into tight sealing contact with the door frame, particularly in connection with relatively heavy overlap doors, a plurality of latching devices are used. They are all similar to the one described in detail. In Figure 1, three are shown. These latching devices are of well known construction and applicant's invention has particularly to do with the latching and releasing mechanism for latches of this general type.

The bracket 12 is provided with a bearing collar 16. There is also a bracket 17 which is attached to the outer face of the door and is provided with projecting portion 18 that extends for a short distance along the edge portion of the door. This bracket 17 carries the bearing collar 19. Mounted in the bearing collars 16 and 19 is a pin 20. This pin is provided with a wedge shaped end 21 which is adapted to engage the tapered outer face 22 on the head 7 of the keeper 6. This pin 20 is normally moved outwardly by a spring 23. The spring bears at one end against

3
the bearing collar 16 and the other end against an abutment washer 23^a which contacts a lug 23^b carried by the pin 20. It is understood that there is a pin 20 associated with each latching device when more than one latching device is used.

The bracket 17 is provided with spaced ears 24, 24. A rod 25 is mounted in these ears and lever 26 is fixed to the rod 25. Said lever 26 has a projecting portion 27 which is adapted to engage the outer end of the releasing pin 20. When there are three latch devices then there are three latch releasing pins 20 and three levers 26 for operating the latch releasing pins. These actuating levers are all attached to the rod 25, and one of the levers is extended so as to provide a handle portion 28 which is bent upon itself as indicated at 29, and bears on the end of a rod 30. There is a spring 31 which normally turns the rod 25 so as to cause the end 29 of the handle portion to bear against this rod 30.

When it is desired to release the latches so that the door may be opened, the operator grasping the handle 28 will turn the rod 25 in a counter-clockwise direction and cause the nose end 27 of the releasing levers to force the releasing pins against the keeper and to force the keepers back into the housings so as to free the end of the keepers with the associated holding lugs 13. During this movement of the levers the handle 28 will be moved away from the door, but as soon as the latches are released and the door is free, then a further pull on the handle will open the door. The rod 30 may be passed through the door and thus the handle member 28 actuated from inside the door to release the latches if desired.

This type of door as noted above is made of varying thicknesses depending upon the place of use and the temperature conditions under which it is used. The latching and releasing mechanism, however, may be used in connection with any thickness of door. It is initially made of sufficient length for the maximum thickness of door. For a door of less thickness a portion is 45

cut off from the upper end of the latch releasing pin and no other changes or modifications are necessary. In the applying of the latch releasing mechanism to a door of given thickness, the amount cut off from the end of the latch releasing pin corresponds to the change in the thickness of the door.

It is obvious that many changes may be made in this latch releasing mechanism without departing from the spirit of the invention as set forth in the appended claim.

I claim:

15 A latching and releasing mechanism for refrigerator doors of the overlapping type comprising a spring actuated keeper mounted on the door frame, a holding lug mounted on the edge of the door adjacent the inner face thereof for wedging engagement with the keeper on the door frame for holding the door closed, a keeper releasing pin mounted in bearings on the edge portion of the door for endwise movement transversely thereof, said pin having a tapered end face for wedging engagement with the keeper for forcibly retracting the same from engagement with the holding lug on the door, a spring for holding the pin out of engagement with the keeper, so as to permit free movement of said keeper to locking position, and a manually operated lever mechanism mounted on the outer face of the door and having a projecting portion adapted to engage the outer end of said pin for forcing the pin into engagement with the keeper for releasing the door.

30 JOHN VINCENT JAMISON, JR.
